UNITED STATES PATENT OFFICE

2,477,326

POCKET CLIP AND SHARPENER FOR
LEAD PENCILSRaymond A. Ball, Fort Wayne, Ind., assignor to
Byron F. Novitsky, Fort Wayne, Ind.

Application July 5, 1947, Serial No. 759,147

7 Claims. (Cl. 120—84)

1

This invention relates to improvements in a pocket clip and sharpener for lead pencils of the ordinary type having a shaft of wood and a core of lead.

Generally, combination pocket clips and pencil sharpeners are mounted upon a pencil in one position for use as a clip, and in reverse position when used as a sharpener which necessitates removal of the pencil, reversal of the device, and reinsertion of the pencil to be sharpened.

An object of the instant invention is to provide a pencil sharpener so constructed that it may be used as a pocket clip and adapted to be mounted upon a lead pencil and remain so mounted without necessitating removal of the pencil whether the device is used as a pocket clip or a sharpener for the pencil.

And another object of the invention is to provide a construction consisting of a pencil holder and a sharpener element, pivotally connected therewith, and having latched connection with the holder, arranged so that when the element is used as a sharpener it is secured in latched position during the sharpening operation, and in spring-restrained position while used as a pocket clip.

Other objects and advantages of the invention appear in the following description.

An illustrative embodiment of the invention is shown in the accompanying drawings, in which:

Fig. 1 is a side elevational view of a structure incorporating the invention, mounted upon a pencil with the cutting element in operative position;

Fig. 2 is a vertical elevational view in a plane at right angles to that of Fig. 1, the cutting element being shown in position for sharpening a pencil;

Fig. 3 is another side elevational view of the invention, showing said element in position for use as a pocket clip;

Fig. 4 is a transverse section of Fig. 3 on the line 4—4 thereof;

Fig. 5 is a group of fragmentary cross-sectional views of the cutting element respectively on the lines x—, y—, and z—, indicated in Fig. 2;

Fig. 6 is a fragmentary front elevational view of the upper end of the pencil holder; and

Fig. 7 is a similar view showing a modification of the pencil holder.

2

The illustrative embodiment of the invention consists of a pencil holder, indicated generally by A, formed of thin sheet spring metal shaped to have an upper cylindrical portion 8 and an open channel portion 9 having parallel side flanges 10, the edges 11 of which recede downwardly, and the lower end of the back portion has made therein a notch 12 for the purpose hereinafter referred to.

10 The flanges 10 have projecting perforated ears 13 that are aligned with each other, located adjacent the junctures of the flanges with the cylindrical upper portion of the holder. A longitudinal slit 8' is made in said upper portion of the holder permitting expansion thereof to accommodate a pencil 15 when inserted into the bore of the holder.

15 A cutting element consisting of an elongated plate 16 is provided with lateral trunnions 17 that extend through the perforated ears 13 respectively and constitute fulcrums upon which the cutting element has tilting movement. The upper end portion of the plate is bowed outwardly and constitutes a spring lever 18 that has contact at its distal end with the cylindrical portion 8 of the holder, thus yieldingly limiting the outward swing of the lower portion of the element. The plate 16 has made therein a longitudinal slot 19 to provide an opening through which shavings 20 cut from a pencil are expelled. One marginal edge of the plate adjacent the opening is bent upwardly more or less increasingly from the lower end of the slot to the other so as to form an overhanging lip 20, and the opposite marginal edge is bent downwardly and sharpened to provide a cutting blade 21 which has operative engagement with a pencil when thrust into the holder and axially turned therein.

25 The lower end of the plate 16 has contiguous therewith a backturned extension, the outer extremity of which is curved outwardly and constitutes a clip 22, the upper face of said extension being provided with a projecting tooth 23 that has latching engagement with the channel portion 9 of the holder when the clip is moved into the notch 12 therein. Thus, the element is firmly secured in pencil-sharpening position.

30 In the modification of the holder (Fig. 7) the slit 8' is irregular, there being an offset to provide a notch 24 in one of the opposing walls and

a tongue 25 extending from the other that fits into the notch, the notch and tongue preferably extending diagonally with respect to the holder. In this manner the opposing walls are interlocked so that relative longitudinal movement of the opposing walls is limited and expansion of the cylindrical upper end of the holder is also limited, the purpose being to prevent distortion of the holder by the torque of a pencil during the sharpening operation.

In use, the plate 16 is pressed into the open channel portion 9 between the flanges 10, whereupon the clip 22 enters the notch 24 and becomes latched by engagement of the tooth 23 with the lower end of the holder, and thereby the cutting element is held in pencil-sharpening position. A pencil then is thrust telescopically into the cylindrical upper end of the holder into contact with the cutting blade 21 and manually revolved therein, whereupon the shaft of the pencil and its lead core are shaved into conical form, the debris being expelled through the longitudinal slot 19, after which the clip is sprung out of latched connection with the holder and the pencil then is thrust farther through the holder so its sharpened end protrudes beyond the lower end thereof into writing position. When thus positioned, the upper end of the spring lever bears yieldingly against the upper cylindrical portion of the holder while the clip bears against the pencil. The cutting element, holder and the pencil are then relatively disposed in position for attachment to a pocket 26, by placing the holder and the clip astride the top of the pocket.

Variations from the particular construction above disclosed may be resorted to by the exercise of skill in the art, without departure from the invention.

What I claim is:

1. A pocket clip and sharpener attachment for a lead pencil, said attachment consisting of a pencil holder formed of sheet spring metal shaped to have a split cylindrical upper portion and an open channel lower portion provided with side flanges the edges of which recede downwardly and have alined perforated projecting ears located adjacent the juncture of said cylindrical and channel portions, and a cutting element consisting of a spring metal plate having lateral trunnions projecting through said ears, providing fulcrums for said element, the upper end of said plate having an extension constituting a spring lever, the distal end of which has contact with the cylindrical upper portion of the holder, said plate having a longitudinal slot therein, one marginal edge of said plate, adjacent said slot, being bent to form an upwardly inclined lip and opposing marginal edge being bent downwardly and sharpened to form a cutting blade, the lower end of said plate having contiguous therewith a backturned extension constituting a clip which is provided with a tooth that has latching engagement with the lower end of the holder when the cutting element is moved into pencil-sharpening position, the arrangement being such that when a pencil is thrust into the holder through the cylindrical end thereof against said blade and revolved, the end of the pencil is shaved into conical form and the debris is expelled through said slot.

2. An attachment for a lead pencil consisting of a pencil holder formed of thin sheet material shaped to have a longitudinally split cylindrical upper portion and an open channel lower portion having downwardly receding side flanges pro-

vided with alined ears, and an element pivotally supported by said ears, having a longitudinal slot provided with a cutting blade along one side of said slot, and having at one end a spring lever the distal end of which has contact with the cylindrical portion of said holder and at its other end an inturned extension constituting a clip provided with latching means engageable with the lower end of the holder by which to secure

10 said element in pencil-sharpening position.

3. A lead pencil attachment for sharpening said pencil or securing a pencil in the pocket of a garment, said attachment consisting of a pencil holder having a split cylindrical portion and a contiguous open channel portion, and an element pivotally supported on the holder, having a cutting blade, provided at one end with a spring lever engageable with said cylindrical portion to limit movement of said element in one direction and at its opposite end with means adapted to have latching engagement with the lower end of the holder to secure said element in pencil-sharpening position, adapted when unlatched for securing the holder to said pocket.

25 4. A lead pencil attachment consisting of a pencil holder provided with an upper cylindrical portion having a longitudinal slit and a lower open channel portion and a cutting element pivoted on said holder provided with a longitudinal slot; one marginal portion of the element along said slot being inturned and sharpened to form a cutting edge, one end of said element having a spring lever engageable with the corresponding end of the holder to limit relative movement

30 35 thereof in one direction, and at its opposite end a clip having latching engagement with the opposite end of said holder, the arrangement being such that, when the clip is latched, the element is held in pencil-sharpening position, and when unlatched and applied to the pocket of a garment, the holder is secured thereon.

40 45 5. A lead pencil sharpener and pocket clip consisting of a pencil holder having a split cylindrical part and an open channel portion contiguous therewith, an element pivotally supported on said holder provided with a cutting blade that projects into said channel portion when said element is moved into one selected position, a spring lever on one end of said element engageable with said cylindrical part to limit movement of said element in one direction, and a clip on the other end of said element having latched engagement with said channel portion when moved into another selected position, whereby to hold the cutting blade into contact with a pencil inserted into the holder through said cylindrical part, so the cutting blade engages the pencil when the clip is latched and the pencil is turned.

60 65 6. A lead pencil attachment consisting of a slit tubular pencil holder, one margin thereof, along the slit, having a notch therein, and the opposing margin having a tongue interlocked in said notch, said tongue and notch being disposed diagonally with respect to the holder, thus to limit relative longitudinal movement of the opposing margins and lateral expansion of the holder, and a cutting element pivotally supported on the holder provided with a cutting blade adapted, when the element is in pencil-sharpening position, for operative engagement with a pencil disposed and turned in said holder, the interlocking notch and tongue being adapted to prevent distortion of the holder by torque of the pencil during the sharpening operation.

70 75 7. A lead pencil attachment having a longitu-

dinal slit tubular pencil holder in which a pencil is inserted for longitudinal and rotary movement therein, the opposing margins of the holder along the slit having interlocking means to prevent relative longitudinal movement thereof, and a cutting element pivoted on the holder, which, when moved to a selected position, has operative engagement with a pencil disposed and turned in said holder.
